UNITED STATES PATENT OFFICE.

SAMUEL WEBB, OF GLASSPORT, AND JAMES PEARSON, OF DUQUESNE, PENNSYLVANIA.

FAN.

No. 874,142.

Specification of Letters Patent.

Patented Dec 17, 1907.

Application filed November 18, 1906. Serial No. 343,693.

To all whom it may concern:

Be it known that we, SAMUEL WEBB and JAMES PEARSON, citizens of the United States of America, residing at Glassport and Duquesne, in the county of Allegheny and State of Pennsylvania, have invented certain new and useful Improvements in Fans, of which the following is a specification, reference being had therein to the accompanying drawing.

This invention relates to certain new and useful improvements in fans, and the invention has for its primary object to provide a simple, inexpensive and attractive fan or novelty available for advertising purposes, as well as for amusement and general use.

Another object of this invention is the provision of positive and reliable means in connection with the fan whereby motion may be imparted to the fan when held in the hand of a person, without the usual and tiresome exertion of moving the hand to and fro.

With these and other objects in view, which will more readily appear as the invention is better understood, the same consists in the novel construction, combination and arrangement of parts to be hereinafter more fully described and then specifically pointed out in the appended claims.

Referring to the drawing forming part of this specification, like numerals of reference designate corresponding parts throughout the several views, in which:

Figure 1 is an elevation of our improved fan, Fig. 2 is a detail sectional view of one part of the fan handle, and Fig. 3 is a vertical sectional view of the fan blade or fan proper.

In the accompanying drawing, 1 indicates a fan or fan blade which is obviously made of any design or form and of any suitable material.

2 indicates a piece of wire bent to support or form a standard for the fan or blade, and 3 and 4 designate the parts or members of a handle, which also may be of such material and form as taste may dictate, it being essential, however, that each member be of sufficient strength to retain their shapes under the action of the tension devices herein-after described.

The piece of wire 2 at one end is provided with a loop 5, and at its opposite end is riveted or otherwise secured as at 6 to the blade 1. The piece of wire intermediate its ends is bent to form a loop 7, said loop engaging the lower edge of the blade 1 and a portion

thereof passing through a notch or recess 8 formed in the lower edge of the fan 1.

The parts 3 and 4 which constitute the handle members of our improved fan are connected together intermediate their ends by a piece of bent wire 9 the connection being such as to permit the ends of the handle members to be oscillated in opposite directions with the connection 9 serving as a fulcrum, while the ends of said handle parts 3 and 4 are slotted, as at 10, to receive the ends 11 of cords or strings 12 wound around the piece of wire 2 and secured to the loops 5 and 7, as at 14. The handle parts 3 and 4 are also connected together by coil springs 15 which form tension devices, the piece of wire 2 passing through one of the convolutions of each spring.

By referring to Fig. 1 of the drawing, it will be observed that the cords or strings 12 are oppositely wound upon the piece of wire 2, in order that when the ends of the handle parts 3 and 4 are oscillated with relation to the wire 2, the cords or strings 12 at one end of the wire 2 will be wound upon the wire while the cords at the opposite end will be unwound thereby imparting a rotary movement to the wire 2 and to the fan blade or fan 1. The springs 15 are adapted to normally maintain the handle parts 3 and 4 in a position parallel with the wire 2.

When the handle members are rocked or oscillated to move the ends thereof in opposite directions by applying pressure to either end of the handle, the spring 15 of that end which is being subjected to pressure, and therefore carried in a direction toward the standard 2, is compressed, while the spring 15 at the other end is expanded, thereby placing both ends of the handle under spring tension. When the pressure is reduced, the tension of the springs tends to move the handle members in the opposite direction, thereby rotating the standard and fan in the opposite direction, and if no further pressure is applied the handle members will resume their normal positions. If the latter movement is, however, continued by applying pressure to the opposite end of the handle, a further rotary movement of the fan in the same direction is obtained, the springs 15 being placed under the opposite tension, so that upon release of the pressure, the members will again resume their normal positions.

Among the advantages of this construction are: (1) the handle members are nor-

2 mally retained in a position where a considerable amount of the cord remains wound upon the standard at both ends and with substantially no excessive tension placed thereon owing to the practically equalized pressure of the opposing springs 15; (2) the handle members may be operated by either the index or the little finger of the hand, the former operating at the upper end of the handle, the latter at the lower end, in either case the springs tending to return the members to their normal positions, thereby permitting the user to operate at different ends of the handle as the finger being used becomes tired, without changing the position of the hand; (3) where the opposite ends of the handle receive pressure alternately to increase the number of revolutions of the fan in one direction, the tendency of the springs 15 to return the members to their normal positions will tend to unconsciously cause the proper finger to move in a direction to continue the movement until stopped by the inability to further compress the members, so that a strict attention on the part of the user is not required such as would be necessary were the movement of the handle members obtained solely by pressure applied by the fingers operating at opposite ends of the handle members, and (4) a movement of the entire hand is not required to manipulate the members, the connection 9 serving to support the hand, and thereby providing a structure which is less tiresome in operation, than where the entire hand is required in providing the pressure-applying action.

From the foregoing description, it will be observed that we have devised a novel fan that can be easily manufactured and sold at a comparatively small cost, whereby the fan may be used for advertisement purposes.

What we claim and desire to secure by Letters Patent, is:

1. The combination with a fan blade, of a piece of wire riveted thereto and having a loop engaging and supporting the lower edge of said fan blade, handle parts arranged upon opposite sides of said piece of wire and connected centrally to permit an oscillatory movement of the ends in opposite directions, springs connecting said handle parts on opposite sides of the central connection, and cords or strings connected to the ends of said handle parts and wound upon said piece of wire and attached thereto, said springs being of a form and so positioned relatively to the handle parts and to each other as to place a

spring tension on both ends of the handle parts upon oscillation of said parts in either direction from a neutral position, substantially as described.

2. A fan consisting of a blade, a piece of wire connected thereto and having a loop supporting the lower edge of said blade, handle parts arranged parallel with said piece of wire and connected centrally to form a fulcrum upon which the parts may oscillate, springs connecting said handle parts on opposite sides of the central connection, and cords or strings connecting the ends of said handle parts to said piece of wire to impart a rotary movement thereto when the ends of said handle parts are oscillated, said springs being of a form and so positioned relatively to the handle parts and to each other as to place a spring tension on both ends of the handle parts upon oscillation of said parts in either direction from neutral position.

3. A fan consisting of a blade, a piece of wire secured to said blade, and having a loop supporting the lower edge thereof, handle parts mounted adjacent to and having their normal position parallel with said piece of wire and adapted to have their ends oscillated in opposite directions with relation to said piece of wire, each end of the handle parts having an independent tension support interposed between and connected to said parts and means actuated by the movements of the ends of said handle parts to impart a rotary movement to said blade.

4. The combination with a fan and a wire standard therefor, of handle members located on opposite sides of the standard, said members being mounted to provide an oscillatory movement of the ends in opposite directions, means connected with the ends of the members and to said standard for rotating the latter upon oscillation of the members, and tension devices between and connected to said members, said devices normally retaining said members parallel with said standard in positions substantially free from tension, the oscillatory movement of the members in either direction applying tension to both ends of the members.

In testimony whereof we affix our signatures in the presence of two witnesses.

SAMUEL WEBB.
JAMES PEARSON.
